Primary Examiner—Philip S. Hyder(74) *Attorney, Agent, or Firm*—Hamre, Schumann, Mueller & Larson, P.C.(57) **CLAIM**

The ornamental design for a sander tool, as shown and described.

DESCRIPTION

FIG. 1 is a perspective view of a sander tool showing our new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a bottom plan view thereof.

The broken lines are included for the purpose of illustrating unclaimed subject matter and form no part of the claimed design.
